UNITED STATES PATENT OFFICE

120,104

DESIGN FOR A HOT WATER HEATER

Lewis Norman Burnside, Philadelphia, Pa., assignor to The Delaware, Lackawanna & Western Coal Company, New York, N. Y., a corporation of New Jersey

Application May 3, 1939, Serial No. 84,770

Term of patent 14 years

To all whom it may concern:

Be it known that I, Lewis Norman Burnside, a citizen of the United States, residing at Philadelphia, in the county of Philadelphia and State of Pennsylvania, have invented a new, original, and ornamental Design for a Hot Water Heater, of which the following is a specification, reference being had to the accompanying drawing, forming part thereof. The dominant features of my design reside in the portions shown in full lines.

Figure 1 is a front elevational view, and Figure 2 is a side elevational view of a hot water heater, showing my new design.

I claim:

The ornamental design for a hot water heater, substantially as shown and described.

L. N. BURNSIDE.
